JOSEPH KAUTZKY, SR., OF FORT DODGE, IOWA

SINGLE TRIGGER MECHANISM

Application filed June 22, 1931. Serial No. 546,037.

The object of this invention is to provide an improved single trigger mechanism for double-barrel guns of the "over-under" type, or in other words—that type of gun in which one barrel is positioned above the other.

A further object of the invention is to provide an improved single trigger mechanism for a double barrel gun so constructed and arranged that when the trigger is pulled to discharge either barrel the mechanism will act automatically to position the parts relative to the trigger for the discharge of the other barrel when the trigger is again pulled.

The invention also includes as one of its objects an improved selecting mechanism whereby either of the two barrels of the gun may be fired first by operation of a single trigger.

Still another object is to provide an improved arrangement of parts for preventing immediate discharge of the second barrel after the discharge of the first barrel of a double barrel gun through the recoil from the shoulder of the operator.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:—

Figure 1 is a longitudinal section showing a gun lock embodying my improved single trigger mechanism, showing the parts in the positions assumed after the firing of the first barrel and before the trigger has been released, so that the parts are locked against inadvertent discharge of the second barrel.

Figure 2 is a cross section on the line 2—2 of Figure 1.

Figure 3 is a detail horizontal section on the line 3—3 of Figure 1, illustrating particularly the selecting mechanism for determining which barrel shall be fired first.

Figure 4 is a detail longitudinal section of a portion of the mechanism, showing particularly the trigger and parts carried thereby.

Figure 5 is an elevation of the mechanism,

partly in section, showing the parts in position for firing the second barrel when the trigger is pulled.

The numeral 10 is employed to designate generally the frame of the gun lock. The frame 10 supports at its forward end the barrels 12 and 14, which are arranged one above the other. The frame includes at its rear portion a top bar 16 and a bottom bar or trigger plate 18 which are connected at their rear ends by a vertical cross bar 20, beyond which is the stock 22 of the gun. Most of the mechanism is arranged within the space between the top bar 16, trigger plate 18 and rear cross bar 20 and is enclosed by portions 24 of the stock extending forward on each side to meet the rear face of the frame.

Pivoted supported on the frame and extending over the top bar 16 is a top lever 26 operating a bolt mechanism 28. The primary function of the top lever 26 is, upon being moved laterally in one direction, to permit breaking of the gun for loading and for cocking the hammers.

Hammers 30 and 32 are pivoted in the frame at 34 in a conventional manner and are adapted to engage firing pins 36 and 38 respectively for the upper barrel 12 and lower barrel 14.

In this type of mechanism the sears 40 and 42 are located above the hammers and are pivoted at 44 on the top bar 16. Each sear is formed intermediate of its ends with a downwardly projecting tooth 46 adapted to engage in a sear notch 48 in the top of one of the hammers for holding it in cocked position. Coil springs 50 are provided for yieldingly urging the sears toward the hammers, these springs being located between the sears and the top plate rearwardly of the pivot 44. Each hammer is formed with a rearwardly projecting tail piece 31 which engages the curved forward face of its sear when it has been pulled and the hammer is down with its projecting tail piece directly under the sear, holding it up out of the way for the pull of the second sear.

When released the hammers 30 and 32 are forcibly moved to firing position by means of main springs 52 and 54 respectively, these

main springs being coiled on rods 56 engaging the rear sides of the respective hammers and slidably engaging in openings in the rear cross bar 20.

A trigger 58 is pivoted at 60 in a slotted opening in the trigger plate 15 and is formed with an upward extension 62 adapted to be raised above the trigger plate when the trigger is pulled.

A pair of firing posts 64 and 66 are mounted side by side and in substantially vertical positions rearwardly of the hammers 30 and 32. The posts have their lower ends loosely mounted in a supporting plate 68 which is mounted on and extends transversely of the trigger plate 18 and bridges the trigger slot. The posts extend nearly to the top bar 16 and are arranged for limited vertical movement when the trigger is pulled and thereby raised at its rear end. The firing posts extend loosely through notches 70 in the rear end portions of the respective sears 40 and 42 and each of said sears is formed with a shoulder 72 beneath the corresponding sear and adapted to raise the latter at times for releasing it from the hammer with which it is engaged by means of its tooth 46 in the sear notch 48.

A firing block 74 is arranged in substantially vertical position behind the firing posts 64 and 66 and is pivoted at its lower end on the projection 62 of the trigger by means of a pin 76. The block 74 is normally urged to forwardly tilted position by a light coil spring 78 mounted in a recess in the block and engaging the projection 62 at a point rearwardly of the pivot 76.

At times the block 74 is held in rearwardly tilted position as indicated by dotted lines in Figure 1, by means of a leaf spring 80 which projects forwardly from the rear cross bar 20 and has at its forward end a hook portion engaging a lateral projection or lug 82 on the upper end portion of the block.

The block 74 is formed on its forward face with a thin forwardly projecting wing 84 which lies between the posts 64 and 66. The forward edge of the wing 84 is adapted to be engaged by a projection 86 on a bar 88 which is slidably mounted on the forward portion of the trigger plate 18. The bar 88 is suitably connected at its forward end to the bolt mechanism 28 so that it is moved rearwardly when the top lever 26 is oscillated manually to unlock and permit breaking of the gun. This rearward sliding movement of the bar 88 serves to swing the firing block 74 rearwardly, by engagement of the projection 86 with the wing 84, until the lug 82 on the said block is in position to be engaged by the spring 80, thereby serving to hold the block in its rearwardly tilted position.

My invention contemplates that the first barrel of the gun is to be fired through the agency of one of the firing posts and the

second barrel of the gun is to be fired through the agency of the block 74. It is for this reason that the block is held in rearwardly tilted or inoperative position until after the first barrel has been fired. When the trigger is pulled for firing the first barrel the projection 62 is slightly raised, thereby elevating the block 74 sufficiently to permit the lug 82 to clear the hook on the spring 80, whereupon the spring 78 will function to swing the block forwardly toward the posts 64 and 66. It will be noted that the block 74 is of sufficient width to extend beneath the rear portions of both of the sears 40 and 42.

One only of the firing posts 64 and 66 is elevated by any given movement of the trigger, this lifting movement being accomplished through the agency of a selecting mechanism interposed between the trigger and the lower end of either one of the posts whereby the desired barrel of the gun will be fired.

The selecting mechanism is shown particularly in Figure 3 and it includes a horizontally arranged selecting lever 90, pivoted between its ends at 92 on the upper face of the trigger 58. The lever 90 is provided at its forward end with a thumb piece 94 which projects through the trigger slot in front of the trigger and is adapted to be manually engaged for moving the lever to either of its selected positions. When so moved, the rear end portion of the selecting lever will be engaged beneath the lower end of one or the other of the firing posts 64 and 66, and will provide a means for lifting such post when the trigger is pulled. The other one of the posts will not be raised because its lower end is spaced sufficiently from the trigger to avoid lifting contact. Stop pins 96 and 98 are provided on the upper face of the trigger and on opposite sides of the pivot 92 for limiting the swinging movement of the selecting lever in either direction.

A friction pin 93 is slidably mounted in the forward end of the trigger 58 and is backed by a coil spring 95. The end of the spring 93 frictionally engages the selecting lever 90, which is L-shaped and embraces the forward end of the trigger, and this frictional engagement serves to hold the lever in the selected position.

In operation the selecting lever is placed in position for first firing the desired barrel of the gun upon the first pull of the trigger.

The movement of the top lever 26 to permit breaking of the gun also acts to move the firing block 74 to rearwardly tilted position through the action of the sliding bar 88 as previously described, and the block is held in this position by the spring 80.

Thereafter, rearward pull on the trigger 58 will cause one or the other of the firing posts 64 or 66 to be raised through the instrumentality of the interposed rear end of the

selecting lever 90, and this upward movement of the post, through its shoulder 72, acts to raise the rear lever of the corresponding sear 40 or 42 and thereby release the hammer which had been held in cocked position by said sear.

This pull on the trigger also causes the firing block 74 to be released from the holding spring 80, through a slight upward movement of the trigger projection 62, and the block is thus permitted to swing forwardly. However, the firing block does not immediately move to operative position beneath the sears, but it still held inoperative so long as pressure is exerted on the trigger after the initial pull. This is to prevent inadvertent firing of the second barrel of the gun through recoil from the operator's shoulder before the operator has had time to remove his finger from the trigger.

It will be noted that the sears 40 and 42 taper to sharp points at their rear ends, which ends project behind the posts 64 and 66. It will also be noted that the tail piece 31 on the hammer which has been released is in engagement with the curved forward face of its sear so that it holds the pointed rear end of said sear in slightly elevated position with respect to the other sear which is still holding its hammer in cocked position. This arrangement is clearly shown in Figure 1. The firing block 74 is formed at its upper forward corner with a forwardly projecting tooth 75, which is capable of entering the space between the pointed ends of the sears when the sears are in the two different positions just described.

As the firing block 74 swings forwardly on its pivot after having been released from the hooked holding spring 80, it is in sufficiently elevated position, because of the continued pull on the trigger 58, that its tooth 75 will enter the space between the rear points of the two sears, thereby preventing the block from passing beneath the sear which is still in operative position. However, as soon as pressure is released from the trigger it will return to its normal position, thus permitting the firing block to move downwardly and still 50 farther forwardly and come to a position beneath the rear points of the sears and in engagement with that one of the sears which is still in holding position.

In this connection it should be noted that the trigger 58 is normally held in its lowered position by means of a spring 100 coiled on a pin 102, which has its upper end seated in a recess in the forward face of the rear cross bar 20. The lower end of the rod 102 is bifurcated at 104 and this bifurcated portion straddles the rear end portion of the trigger projection 62, engaging in a notch 106 in the upper face of said projection.

Now when the trigger 58 is pulled a second time it will operate to raise the firing

block 74 which in turn will elevate the rear end of the other sear such as 40, thereby releasing the second hammer such as 30 and firing the other barrel of the gun.

It will be observed that in any given position of the selecting mechanism one only of the firing posts 64-66 is employed for releasing a sear and that the other sear is released by action of the firing block 74 which is of such character as to operate upon either one of the sears which may be still in holding position when the firing block is in position for operation. It will be understood that if the firing block were not held inoperative by the spring 80, both sears would be conjunctively raised and both barrels would be fired at the first pull of the trigger, but this cannot ordinarily occur because the firing block is moved to inoperative position by the operation of the top lever 26 preliminary to cocking the gun.

I claim as my invention:—

1. In a gun lock, a frame, a pair of hammers pivoted therein, a pair of spring pressed sears pivoted in the frame above the respective hammers adapted to engage said hammers and hold them in cocked position, a trigger pivoted at its forward end in the lower part of the frame, a firing post mounted above said trigger and adapted to be lifted when the trigger is pulled, said post having a part to engage one of said sears for releasing it from its hammer, a firing block pivoted on the rear end of the trigger and adapted to engage beneath the other sear for releasing it from its hammer, means for retaining said firing block in inoperative position temporarily, said block being released from said holding means by the first pull on the trigger, and yielding means for moving said block toward operative position when so released.

2. In a gun lock, a frame, a pair of hammers pivoted therein, a pair of spring pressed sears pivoted in the frame above the respective hammers adapted to engage said hammers and hold them in cocked position, a trigger pivoted at its forward end in the lower part of the frame, a pair of firing posts mounted above said trigger and arranged for limited vertical movement, each post having a part to engage one of the sears for releasing it from its hammer, a selecting lever arranged for manual actuation and having a part adapted to be interposed selectively beneath one of said posts whereby the selected post will be lifted when the trigger is pulled, a firing block pivoted on the rear end of the trigger and adapted to engage beneath the sears at times, said block being movable to inoperative position until after the first hammer has been released, a spring latch for holding said block in inoperative position, said block being disengaged from said latch by lifting movement occasioned by the first pull on the trigger, and yielding means

tending to move said block toward operative position.

3. In a gun lock, a frame, a pair of hammers pivoted therein, a pair of spring pressed sears pivoted in the frame above the respective hammers adapted to engage said hammers and hold them in cocked position, a trigger pivoted at its forward end in the lower part of the frame, a pair of firing posts mounted above said trigger and arranged for limited vertical movement, each post having a part to engage one of the sears for releasing it from its hammer, a selecting lever arranged for manual actuation and having a part adapted to be interposed selectively beneath one of said posts whereby the selected post will be lifted when the trigger is pulled, a firing block pivoted on the rear end of the trigger and adapted to engage beneath the sears at times, said block being movable to inoperative position until after the first hammer has been released, a spring latch for holding said block in inoperative position, said block being disengaged from said latch by lifting movement occasioned by the first pull on the trigger, and yielding means tending to move said block toward operative position, said block being formed with a part for engaging above the rear end of the unreleased sear to hold it momentarily out of operative position beneath the sear, until such time as pressure on the trigger has been released.

4. A mechanism of the character described including a pair of pivoted spring pressed hammers, a pair of sears adapted to engage the hammers for holding them in cocked position, a pivotally mounted trigger, a pair of like firing members each arranged to engage and release one of the sears, a third firing member arranged to be moved by said trigger for engaging and releasing either one of the sears, a selecting member capable of being positioned to cause one or the other of the first named firing members to be moved by the trigger for operating upon the selected sear, and means for latching the third firing member in inoperative position, said latching means being released by a pull on the trigger to permit said third firing member to move toward operative position.

5. A mechanism of the character described including a pair of pivoted spring pressed hammers, a pair of sears adapted to engage the hammers for holding them in cocked position, a pivotally mounted trigger, a pair of like firing members each arranged to engage and release one of the sears, a third firing member arranged to be moved by said trigger for engaging and releasing either one of the sears, a selecting member capable of being positioned to cause one or the other of the first named firing members to be moved by the trigger for operating upon the selected sear, and means for latching the third firing

member in inoperative position, said latching means being released by a pull on the trigger to permit said third firing member to move toward operative position, the last named firing member being formed with a part for holding it out of operative position relative to the sears, after the latch is released, until such time as the trigger has returned to normal position.

6. In a mechanism of the character described, a pair of pivoted spring pressed hammers each formed with a sear notch, a pair of sears pivotally mounted and each formed with a part for engaging the sear notch of a hammer for holding the latter member in cocked position, a pair of firing posts arranged for limited movement beneath the respective sears and each formed with a part for moving one of the sears to releasing position, a trigger pivoted beneath said posts but spaced at all times therefrom, a selecting member adapted to be positioned between the trigger and one or the other of said posts to provide an operative connection whereby the selected post is raised by pulling the trigger and thereby releasing the corresponding sear, a third firing member pivoted on the rear portion of the trigger and adapted to engage beneath both sears, yielding means tending to move the third firing member to a position beneath the sears, and latching means for holding the third firing member in inoperative position, said latching means being releasable by a pull on the trigger to permit said third firing member to move to operative position for releasing the remaining sear upon a subsequent pull of the trigger.
